BEAM OR GIRDER CONSTRUCTION

Albert L. Lambert, Narberth, Pa., assignor to
Heintz Manufacturing Company, Philadelphia,
Pa., a corporation of Pennsylvania

Application April 13, 1934, Serial No. 720,350

4 Claims. (Cl. 189—34)

This invention relates to beam or girder construction, and one of the principal objects of this invention is to provide a beam or girder construction and method of assembly, which permits assembly of sections of structure, for instance, deck or roof sections, at a shop or plant, and the installation of the sections, as such, in their final location thereafter; and a further object of this invention is to provide a beam or girder construction comprising sections adapted to be united to form a rigid and sturdy beam or girder; and another object of this invention is to provide a beam or girder comprising sections each adapted to be pre-assembled to a different structure section or unit, and adapted on final installation to be united in a variable relationship, whereby errors of assembly, both in the assembly of the structure sections or units in the shop, and in the structure in which the structure sections are finally assembled may be compensated for without impairing the rigidity, strength or effectiveness of the beam, or requiring repositioning or change of any part already in place, or making necessary any distortion of elements or additional strains due to such errors.

A further object of this invention is to provide a beam or girder construction of the character described, and a construction which is comparatively light in weight, is adapted to be built up of sheet metal, is extremely sturdy, rigid and effective and may be finally installed and assembled conveniently, quickly and without great expense.

Another object of this invention is to provide a method of constructing and installing a beam or girder, and assembling and installing structural units associated therewith.

Other objects of this invention will be in part obvious and in part pointed out hereinafter.

In accordance with this invention the beam or girder is made in two disjoined longitudinal sections so that each section may be pre-assembled along an edge of a deck, roof or floor section, or the like, to facilitate shop manufacture and shipping to the place of installation in rather small units, the deck, roof or floor sections being installed in the final structure with the beam sections of different units in proximity, the spacing of the beam sections being variable and in this way errors of assembly both in the factory and on the structure on which the installation is made may be compensated for. Means are provided for rigidly and firmly uniting the compensatingly positioned sections into a rigid and strong beam or girder structure. The width of the beam, so established, compensates for and conceals any assembly errors and avoids any distortion or strains due to any such errors. Obviously the invention may be expressed in many different specific designs and organization of the

disjoined longitudinal sections, as well as in a variety of different specific means for uniting these sections into a permanent beam or girder structure after the longitudinal sections have been properly spaced in accordance with the specific conditions of their location and installation. However, in order that a clearer understanding of this invention may be had, attention is now directed to the accompanying drawings, forming a part of this application, and illustrating certain possible specific embodiments of this invention, and in which:

Fig. 1 is a top plan view of a fragment of deck, roof or floor comprising a plurality of sections and including beam or girder construction embodying this invention;

Fig. 2 is a perspective view, partly in section and partly broken away, of a portion of the structure shown in Fig. 1;

Fig. 3 is a sectional view of a portion thereof, and is taken on the line 3—3 of Fig. 4;

Fig. 4 is a sectional view of a portion thereof, and is taken on the line 4—4 of Fig. 1;

Fig. 5 is an enlarged, centrally broken end view, showing the longitudinal sections united into a permanent beam or girder structure; and

Fig. 6 is a view similar to Fig. 5, showing a possible modification of the beam or girder structure.

Similar reference characters refer to similar parts throughout the several views of the drawings.

Referring to the drawings, each disjoined longitudinal section of the beam or girder, as shown, comprises a vertical longitudinal web plate 1 along the top of which is secured, as by welding, the vertical central web 2 of a Z-shaped strip, having a flange 3 along the bottom edge of web 2 extending therefrom and from web plate 1, and having a flange 4 extending over the top of web plate 1 and terminating in a downwardly extending flange 5. One edge, 6, of a horizontal strip 7 lies on and is secured, as by welding, to the flange 4, this edge 6 preferably being depressed below the remainder of strip 7 so that when the upper portions of the longitudinal beam or girder sections are secured together, in establishing the permanent beam or girder structure, by means of a metal strip 8 seated on portion 6 and welded thereto, as at 9, the top surface of strip 8 may 50 come flush with the top surface of the part of strip 7 which extends outwardly of the web 2.

An angle strip 10 is secured, as by welding, along the lower edge of web 1 and a channel strip 11 is secured, as by welding, to the flange 12 of strip 11, the portion 13 of the channel strip, and which extends inwardly of web 1, being displaced so that when the lower portions of the longitudinal beam or girder sections are secured together, in establishing the permanent beam or girder 60

structure, by means of a metal strip 14 seated against portion 13 and welded thereto, as at 15, the outer, or under, surface of strip 14 may be flush with the under surface of channel portion 11.

The two disjoined longitudinal beam or girder sections are of similar, but complementary, construction, and are adapted to be disposed in variable proximity to each other, as shown. When 10 in position they are adapted to be united by means of the longitudinal strips 8 and 14, which are welded to both sections, thus forming a permanent closed beam or girder structure which is extremely strong and rigid and of a width which 15 is adjusted in accordance with the special conditions of the specific structure in which the beam is installed, and to compensate for errors of assembly.

If desired, the beam sections may be provided 20 with further reenforcement, such as channel pieces 16, secured to web 1, or by any other suitable reenforcing and stiffening members, as desired.

With a segmental beam or girder construction 25 embodying this invention, sections of structure, such as sections of deck, roof, floor, or the like, having a beam section along one or more edges, may be pre-assembled at a shop or plant and then shipped to the place where they are to be used 30 and then installed. For instance, the pre-assembled structural deck, roof or floor sections may comprise, as shown, intermediate beams 20 secured to the main girder sections by means of suitable angle irons or brackets 21 and angle 35 plates 22, and deck or floor plates 23 engaging and secured to the main girder section and the intermediate stiffening beams 20. After these deck, floor or roof sections have been placed in final position with complementary main girder 40 sections of adjacent deck, roof or floor sections in proximity to each other, these complementary girder sections are secured together, as positioned, by placing the uniting strips 8 and 14 along the top and bottom of the girder sections 45 and welding the strips to both sections.

Obviously, the precise form and structure of the pre-assembled deck, roof or floor sections may vary considerably, and these sections at the edges where the sectional beam or girder structure embodying this invention is not provided may be 50 mounted and secured in final location by any suitable means, which are well known and form no part of this invention.

In the modified segmental beam or girder construction illustrated in Fig. 6 and embodying this 55 invention, each main section comprises a vertical web plate 30 having an angle strip 31 extending along the lower edge of and welded to the outside surface of web 30 and having an inverted channel strip 32 extending along the upper edge of and 60 welded to the inner surface of web 30 with the channel disposed inwardly of web 30. A depressed edge portion 33 of an attachment strip 34 seats along and is welded to the body of the inverted 65 channel strip 32. Both beam or girder sections are similar and complementary to each other. These complementary beam or girder sections may be united at the top by means of a metal strip 35 seating along and welded, as at 36, to the 70 portions 33 of both girder sections, and may be united along the lower edges by means of a metal strip or plate 37 which extends along and is welded, as at 38, to the outwardly extending flanges 39 of the angle strips 31. If desired, strip 75 37 may have an upwardly extending flange 40

along each edge to add strength, rigidity and stiffness to the beam or girder.

In either modification of sectional beam or girder construction, shown or described, the means for uniting the two sections together into a permanent, closed beam or girder structure permits the positioning of the sections in variable proximity to each other, that is, the uniting means do not require the beam sections to be precisely a definite distance apart, and permit considerable 10 leeway in this respect. This variation in the width of the final beam or girder structure permitted by the uniting means allows errors of assembly both in the building of the deck, floor or 15 roof sections, and in the structure in which such sections or the beam sections are finally installed, to be compensated for and to be hidden in the final width of the completed beam or girder structure.

As many changes can be made in the construction, and as many apparently widely different embodiments of this invention can be made without departing from the scope of this invention, it is understood that all matter contained in the above 20 description or shown in the accompanying drawings be interpreted as illustrative and not in a limiting sense.

What I claim is:

1. In construction of the character described, 30 in combination, thin plate sections having depending therefrom at their adjacent edges beam forming members, the beam members having ledges, and strips connecting the ledges of adjacent beam members to form continuous plating 35 having a box beam support.

2. In construction of the character described, 40 in combination, thin plate sections having attachment strips along their adjacent edges and having depending from said strips beam forming members, the beam members having ledges along their lower edge portions, and strips connecting adjacent attachment strips and the ledges of adjacent beam members to form continuous plating 45 having a box beam support.

3. A sheet metal box beam or girder of the 50 character described, comprising two longitudinal spaced sheet metal side plates, an angular re-enforcing strip secured along the upper edge of each plate and having an inwardly directed horizontal ledge portion terminating in a depending flange, an angle iron secured along the lower portion of each plate and having an outwardly extending ledge along the lower edge of the plate, a strip connecting the upper ledges of the two upper reenforcing strips together, and a strip 55 connecting the ledges of the two lower angle irons together to form the box beam or girder.

4. A sheet metal box beam or girder of the character described, comprising two longitudinal spaced sheet metal side plates, an angular re-enforcing strip secured along the upper edge of each plate and having an inwardly directed horizontal ledge portion terminating in a depending flange, an angle iron secured along the lower portion of each plate and having an outwardly extending ledge along the lower edge of the plate, a strip connecting the upper ledges of the two upper reenforcing strips together, and a strip 60 connecting the ledges of the two lower angle irons together to form the box beam or girder, and a metal strip secured along each of the upper reenforcing strips and having an outwardly directed attachment portion for deck or roof plates. 65
